US00D843737S

(12) **United States Design Patent** (10) Patent No.: **US D843,737 S**
Moosmann et al. (45) Date of Patent: **** Mar. 26, 2019**

(54) **SIEVE BOX SHEET WITH A SURFACE PATTERN**

(71) Applicant: **Bühler AG**, Uzwil (CH)

(72) Inventors: **Jürgen Moosmann**, Berg (DE); **Marcel Linder**, Flawil (CH); **Daniel Dörig**, Wil (CH)

(73) Assignee: **Bühler AG**, Uzwil (CH)

(**) Term: **14 Years**

(21) Appl. No.: **29/504,625**

(22) Filed: **Oct. 8, 2014**

(30) **Foreign Application Priority Data**

Sep. 4, 2014 (WO) DM/083 423

(57) **CLAIM**

The ornamental design for a sieve box sheet with a surface pattern, as shown and described.

DESCRIPTION

FIG. 1 is a top plan view of a sieve box sheet with a surface pattern, showing a first embodiment of our new design;

FIG. 2 is a top plan view of a sieve box sheet with a surface pattern, according to a second embodiment of our design;

FIG. 3 is a top plan view of a sieve box sheet with a surface pattern, according to a third embodiment of our design;

FIG. 4 is a top plan view of a sieve box sheet with a surface pattern, according to a fourth embodiment of our design; and,

FIG. 5 is a top plan view of a sieve box sheet with a surface pattern, according to a fifth embodiment of our design.

1 Claim, 5 Drawing Sheets
